Des. 179,424
Patented Dec. 18, 1956

179,424

DISPLAY CASE

Tadeusz S. Olejniczak, Trenton, N. J.

Application August 20, 1954, Serial No. 31,953

Term of patent 14 years
(Cl. D80—11)

The figure in the drawing is a perspective view of a display case showing my new design.

The appearance of the display case on the opposite side and end is substantially identical with that of the side and end appearing in the drawing.

The dominant features of the design reside in the portions shown in full line.

I claim:

The ornamental design for a display case, substantially as shown and described.
